(57) **CLAIM**

The ornamental design for a remote control system for keyless access of a vehicle, as shown and described.

DESCRIPTION

FIG. 1 is a top and left perspective view of the remote control system for keyless access of a vehicle showing our new design;

FIG. 2 is a top plan view thereof;

FIG. 3 is a rear side elevation view thereof;

FIG. 4 is a right side elevation view thereof;

FIG. 5 is a left side elevation view thereof;

FIG. 6 is a front side elevation view thereof; and,

FIG. 7 is a bottom plan view thereof.
